(57) **CLAIM**

The ornamental design for a device holder, as shown and described.

DESCRIPTION

FIG. 1 is a perspective view of a first embodiment of a device holder, showing our new design;
FIG. 2 is a front plan view thereof;
FIG. 3 is a side elevation view thereof;
FIG. 4 is a back plan view thereof;
FIG. 5 is a side elevation view thereof, showing the opposite side shown in FIG. 3;
FIG. 6 is a top elevation view thereof;
FIG. 7 is a bottom elevation view thereof;
FIG. 8 is a perspective view of a second embodiment of a device holder, showing our new design;
FIG. 9 is a front plan view thereof;
FIG. 10 is a side elevation view thereof;
FIG. 11 is a back plan view thereof;
FIG. 12 is a side elevation view thereof, of an opposite side shown in FIG. 10;
FIG. 13 is a top elevation view thereof;
FIG. 14 is a bottom elevation view thereof;
FIG. 15 is a perspective view of a third embodiment of a device holder showing our new design;
FIG. 16 is a front plan view thereof;
FIG. 17 is an elevation side view thereof;
FIG. 18 is a back plan view thereof;
FIG. 19 is an elevation side view thereof, of an opposite side shown in FIG. 17;
FIG. 20 is a top elevation view thereof; and,
FIG. 21 is a bottom elevation view thereof.
